UNITED STATES PATENT OFFICE.

EDWARD F. CHAFFEE, OF SYRACUSE, NEW YORK, ASSIGNOR TO THE O. M. EDWARDS COMPANY, INC., OF SYRACUSE, NEW YORK, A CORPORATION OF NEW YORK.

TRAP-DOOR FOR RAILWAY-CAR PLATFORMS.

1,195,779.

Specification of Letters Patent. Patented Aug. 22, 1916.

Application filed December 21, 1914. Serial No. 878,462.

To all whom it may concern:

Be it known that I, EDWARD F. CHAFFEE, a citizen of the United States, and a resident of Syracuse, in the county of Onondaga and State of New York, have invented 5 a certain new and useful Trap-Door for Railway-Car Platforms, of which the following is a specification.

This invention relates to trap doors for 10 railway car platforms, particularly car platforms which are capable of being projected laterally beyond the sides of the cars to bridge the space between the cars and station platforms elevated into a position 15 substantially flush with the car platforms, and it has for its object means movable with the platform to bridge the space between the inner edge of the door and the platform floor when the door is projected 20 outwardly; and the invention consists in the combinations and constructions hereinafter set forth and claimed.

In describing this invention, reference is had to the accompanying drawings, in 25 which like characters designate corresponding parts in all the views.

Figure 1 is a fragmentary view illustrating in plan a portion of the platform, and trap door provided with my invention. 30 Fig. 2 is a section on the plane of line 2—2, Fig. 1, the door being shown as swung into open position on its hinge. Fig. 3 is a fragmentary sectional view taken on the plane of line 2—2, Fig. 1, the door being shown as 35 slid outwardly to its open position, parts of the sliding mechanism for the door being omitted. Fig. 4 is a transverse sectional view through the door on line A—A, Fig. 1. Fig. 5 is a sectional view on line B—B, 40 Fig. 1.

This invention comprises means movable laterally beyond the side of the car and having a portion telescoping with the platform floor of the car. Said means is here 45 shown as a trap door and the telescoping portion thereof is a slide coupled to the trap door at the inner edge thereof.

1 designates the car platform.

2 designates the trap door which is 50 hinged at one side of the door opening and which is movable axially of its hinge to project its outer portion 3 beyond the side face 4 of the car.

The door is hinged to the platform in any 55 well known manner, it being here shown as

provided with parallel levers 5 which support the floor of the trap door and which are pivoted at 6 at their inner ends to bearings 7 fixed upon a spring barrel 8 journaled in bearings 9, 10, carried by the platform. The parallel levers 5 are connected 60 at their outer ends to the under side of the flooring of the door by pins 11 extending through slots in the levers. During axial shifting of the door the levers 5 move in parallelism on their pivots 6 and guide the door in its sliding movement. A suitable torque spring 13 is fixed at one end to one bearing and at its other end suitably connected to the spring barrel to rotate the barrel 65 to open the door on its hinge. The support for the door forms no part of this invention. 70

The door is slidably axially when in its closed position by any suitable means here 75 shown as a vertical rock shaft 14 supported by the platform and having a rock arm 15 thereon which is connected by a link 16 to the trap door flooring. The rock shaft is provided with a suitable folding handle 17 80 by means of which it is operated.

The means for bridging the space between the inner edge of the trap door 2 and the floor of the platform at the top of the trap door opening, as here shown consists 85 of a slide 18 which telescopes with the platform. Said slide is preferably connected to the door 2 by a coupling which disconnects the door from the slide 18 during the opening movement of the door and which connects the door to the slide as the door approaches its closed position. As here shown, the slide 18 is movable into and out of a horizontal cavity 19 beneath the tread 90 of the platform 1 at the top of the step opening, the cavity being provided with suitable braces 20 therein for supporting the tread of the platform 1, these braces being usually of angle iron. The slide 18 is formed with slots 21, complementary to the 95 braces 20. Supports 22 for the slide are also provided on the bottom of the cavity 19 and on which the slide 18 rests while in the cavity and during its sliding movement.

When the slide 18 is moved out of the 100 cavity, as when the door 2 is moved axially, that is, longitudinally of its axis, the opposite edges of the slide rest on ledges 23, 24, Figs. 1 and 4, provided on the platform and 105 on the hinge barrel 6. The free edge of the 110

door normally rests on a ledge 25 in the ordinary manner, and the ledge 23 is an extension of the ledge 25 at the inner end thereof, and its surface is depressed below the surface of the ledge 25, as the slide 18 has a portion extending under the tread of the door 2. The door is coupled to the slide by interlocking means which move out of and into interlocking engagement during the opening and closing of the door on its hinge. As here shown, said means comprises eyes or openings 26 provided in one of the parts coupled together, as the slide and lugs 27 provided on the other of said parts as the door, the lugs 27 being carried by brackets 28 projecting beyond the inner edge of the door. The eyes 26 are alined with cutouts 29 in the platform 1, which cutouts receive the lugs 27 so that the upper faces of the lugs 28 are flush with the upper face of the slide 18.

The slide is held from movement when the door is uncoupled therefrom by suitable locking means operated by the door, and as here shown, said means consists of a spring pressed bolt 30 supported by the platform and arranged to enter one of the eyes 26 as the lug 27 moves out of said eye and to be depressed out of the eye 26 by said lug 27 as the door approaches its closed position.

In operation, when a train stops at a station having the platform near the level of the tracks, the trap door is opened in the usual manner permitting the passengers to alight and board by means of the steps, and during the opening of the trap door, the lugs 27 move out of the openings 26 of the slide and the bolt 30 moves into one of the openings 26 holding the slide 18 in its normal position. During the closing of the door 2 on its hinge, the lugs 27 come into interlocking engagement with the eyes 26 and again couple the door 2 and the slide 18.

When the train stops at stations having elevated platforms near the level of the car platform, the rock shaft 14 is operated to shift the door 2 outwardly and axially so that its outer portion 3 projects beyond the side of the car, and as the door 2 moves, the slide 18 moves out of its cavity 19, and bridges the space between the inner edge of the trap door 2 and the platform 1.

When the train departs, the rock shaft 10 is again operated moving the door 2 axially and again moving the slide 18 into the cavity 19. During the sliding movement of the slide 18, it moves on the ledges 23 and 24.

What I claim is:

1. The combination with a railway car platform, of a trap door hinged to the platform at one side of the door opening, and slideable longitudinally of the axis of its hinge, and a slide located at the inner edge of the door to bridge the space between the

platform and the door when the door is moved axially outwardly from its normal position, the door being separated from the slide during the opening and closing movement of the door about its hinge, substantially as and for the purpose described. 70

2. The combination with a railway car platform having a cavity at the top of the platform steps, and a trap door hinged to the platform at one side of the door opening and shiftable longitudinally of the axis of its hinge, the door having means associated therewith and movable into and out of the cavity during the axial movement of the door, the door being separated from said means during the movement of the door on its hinge, substantially as and for the purpose specified. 75

3. The combination with a railway car platform, of a trap door hinged to the platform at one side of the door opening and slideable longitudinally of the axis of its hinge and means at the inner edge of the door telescoping with the platform at the top of the steps of the platform, the door being separated from said means during the opening movement of the door on its hinge, substantially as and for the purpose set forth. 80

4. The combination with a railway car platform, of a trap door hinged to the platform at one side of the door opening and slideable longitudinally of the axis of its hinge, a slide located at the inner edge of the door to bridge the space between the platform and the door when the door is moved outwardly axially, and means coupling the door and the slide and acting to disconnect the door from the slide during the opening of the door on its hinge and to connect the door and the slide as the door approaches its closed position, substantially as and for the purpose described. 90

5. The combination with a railway car platform, of a trap door hinged to the platform at one side of the door opening, and a slide located at the inner edge of the door and telescoping with the platform at the inner side of the door opening, the door and the slide having means moving into and out of interlocking engagement during the opening and closing of the door, substantially as and for the purpose specified. 110

6. The combination with a railway car platform, of a trap door hinged to the platform at one side of the door opening, and a slide located at the inner edge of the door and telescoping with the platform at the top of the steps, the door and the slide having means moving into and out of interlocking engagement during the opening and closing of the door, said means consisting of an opening provided on one of said parts connected together, and a lug provided on the other of said parts, the lug and opening 125

being arranged at an angle to the sliding movement of the door and being arranged to come into engagement as the door approaches its closed position, substantially as and for the purpose set forth.

5 7. The combination with a railway car platform, of a trap door hinged to the platform at one side of the door opening, a slide located at the inner edge of the door and telescoping with the platform at the top of the steps, the door and the slide having means moving out of and into interlocking engagement during the opening and closing of the door, and means for holding the slide 10 from movement when the door is swung open on its hinge, substantially as and for the purpose described.

8. The combination with a railway car platform, of a trap door hinged to the platform at one side of the door opening, a slide located at the inner edge of the door and telescoping with the platform at the top of the steps, the door and the slide having means moving out of and into interlocking engagement during the opening and closing of the door, and means for holding the slide 15 from movement when the door is swung open on its hinge, substantially as and for the purpose described.

9. The combination with a railway car platform, of a trap door hinged to the platform at one side of the opening and being slidable longitudinally of the axis of its hinge, a slide located at the inner edge of the door and telescoping with the platform at the inner end of the door opening, the slide 20 being provided with an eye opening, and the door being provided with a lug, the opening and the lug being arranged at an angle to the sliding movement of the door, and arranged to come into interlocking engagement 25 as the door approaches its closed position, and a lock associated with the platform and arranged to enter the opening as the lug

moves out of the opening to hold the slide from movement when the door is opened and to move out of the opening as the door approaches its closed position, substantially as and for the purpose set forth.

10. The combination of a railway car platform having a cavity at the inner end of the door opening, a brace interposed between the floor of the platform and the bottom of the cavity, a trap door hinged to the platform at one side of the door opening and slidably lengthwise of the axis of its hinge, and a slide located at the inner edge of the door and movable into and out of the cavity and having a slot into which the brace extends, substantially as and for the purpose described.

11. The combination with a railway car platform, of a trap door hinged at one side of the door opening and including a spring barrel on the underside thereof, the door being also movable lengthwise of the axis of the barrel, a slide telescoping with the platform at the inner side of the door opening, means coupling the slide and the door together whereby the slide is movable axially with the door, and means carried by the hinge barrel for supporting the slide during the sliding movement of the door and the slide, substantially as and for the purpose specified.

12. The combination with a railway car platform, formed with a cavity at the top of the steps of the platform, of means movable laterally beyond the side of the car and having a portion movable into and out of said cavity, substantially as and for the purpose set forth.

In testimony whereof, I have hereunto signed by name, in the presence of two attesting witnesses, at Syracuse, in the county of Onondaga and State of New York, this 10th day of November, 1914.

EDWARD F. CHAFFEE.
